CLAIM

The ornamental design for a garden tool for removing rooted plants, as shown and described.

DESCRIPTION

FIG. 1 is a front elevational view of a garden tool for removing rooted plants showing my new design with the rear view being a mirror image;

FIG. 2 is a side elevational view thereof with the opposite side being a mirror image thereof;

FIG. 3 is a top plan view thereof;

FIG. 4 is a bottom plan view thereof;

FIG. 5 is an enlarged, detailed elevational view of the prong assembly of FIG. 1; and

FIG. 6 is an enlarged, detailed bottom plan view of the prong assembly of FIG. 1.

The broken lines showing the ground in FIG. 5 are for illustrative purposes only and form no part of the claimed design.
